UNITED STATES PATENT OFFICE

159,964

BOX FOR MEDALS OR THE LIKE

Arthur E. Du Bois, Washington, D. C., and Robert R. Wilson, Ashtabula, Ohio, assignors to the United States of America as represented by the Secretary of the Army

Application June 19, 1946, Serial No. 130,865

Term of patent 14 years

(Cl. D58—12.6)

To all whom it may concern:

Be it known that we, Arthur E. Du Bois and Robert R. Wilson, citizens of the United States and residents of the city of Washington, in the District of Columbia, and the city of Ashtabula, in the county of Ashtabula and State of Ohio, respectively, have invented a new, original, and ornamental Design for a Box for Medals or the like, of which the following is a specification, reference being had to the accompanying drawings, forming a part thereof.

Fig. 1 is a perspective view of a box for medals or the like, showing our new design;

Fig. 2 is a front view thereof as it appears in closed position;

Fig. 3 is a rear view thereof;

Fig. 4 is a side view;

Fig. 5 is a bottom view;

Fig. 6 is a top view; and

Fig. 7 is a fragmentary sectional view thereof taken on line 7—7 of Fig. 4 and illustrating the contrasting groove on the inside of the cover.

We claim:

The ornamental design for a box for medals or the like, as shown.

ARTHUR E. DU BOIS.
ROBERT R. WILSON.
